UNITED STATES PATENT OFFICE.

WILLIAM BUCHWITZ, OF BROOKLYN, NEW YORK, ASSIGNOR TO GOLDING BROS. COMPANY, OF NEW YORK, N. Y., A CORPORATION OF NEW YORK.

DESIGN FOR A FABRIC.

Application filed November 11, 1922. Serial No. 4,258. Term of patent 7 years.

To all whom it may concern:

Be it known that I, WILLIAM BUCHWITZ, a citizen of the Republic of Germany, residing at Brooklyn, in the county of Kings and State of New York, have invented a new, original, and ornamental Design for a Fabric, of which the following is a specification, reference being had to the accompanying drawings, forming a part thereof.

The figure is a plan view of a section of the textile fabric embodying my new design.

I claim:

The ornamental design for a fabric, as shown.

WILLIAM BUCHWITZ.
